UNITED STATES PATENT OFFICE.

FLOYD L. SWANBERG, OF CINCINNATI, OHIO, ASSIGNOR TO THE D. T. WILLIAMS VALVE COMPANY, OF CINCINNATI, OHIO, A CORPORATION OF OHIO.

GENERATOR-VALVE FOR GASOLENE-ENGINES.

994,886.

Specification of Letters Patent. Patented June 13, 1911.

Application filed December 27, 1907. Serial No. 408,236.

To all whom it may concern:

Be it known that I, FLOYD L. SWANBERG, a citizen of the United States, residing in Cincinnati, in the county of Hamilton and State of Ohio, have invented certain new and useful Improvements in Generator-Valves for Gasolene-Engines, of which the following is a full, clear, and exact description, reference being had to the accompanying drawings, forming part of this specification.

My invention relates to generator or mixing valves for gasoline engines more particularly adapted for use with marine gas engines of the two cycle type, although, of course, so far as the improvements are adapted for supplying the proper mixture of gas and air to any type of engine, my invention is not to be understood as limited to marine engines whether of one type or another.

My improvements consist of the novel construction and arrangement of parts which will be hereinafter particularly pointed out and claimed which embody features of construction whereby the proper mixture of gas and air may be furnished for either high or low speeds and in which the liability of leakage of the gasoline when the engine is at rest is overcome.

In the drawings Figure 1 is a central vertical section of my improved generator taken at right angles to the gasoline valve. Fig. 2 is a similar horizontal section of same. Fig. 3 is a central vertical section taken at right angles to the section shown in Fig. 1 and Fig. 4 is a vertical section taken through the throttle valve. Fig. 5 is a horizontal section taken on lines 5—5 of Fig. 3.

1 is a cylindrical metal casing forming the mixing chamber 2, and provided with an inlet pipe 3, secured in the base, gasoline inlet pipe 4, secured at one side, and the 45 ejection port 5, for the mixture from the mixing chamber 2, to the engine cylinder.

6 is the air inlet valve comprising a disk 7, having its seat in the base 8, of the mixing chamber, and provided with a hollow 50 stem 9, which is guided in the socket 10 of the bushing 11, depending from the screw threaded cap 12, which closes the upper end of the mixing chamber.

The gasoline is supplied through pipe 4, 55 through the inlet port 13, which is formed

in a tubular casing 15, which extends across the air inlet port below the seat of the air inlet valve, and the supply of gasoline is controlled by the needle valve 14, provided with screw threaded stem 16, and knurled head 17, the valve being held in set position by the spring plate 18, secured by a nut 19, while 20 is the packing with stuffing box cap 21, for the valve stem. A passage 22, for the gasoline is drilled into the needle valve 65 opening and leads vertically upward under the air inlet valve 6. This passage is closed by the needle check valve 23, which is provided with a stem 24, which is loosely guided in the hollow socket of the valve stem 9, 70 of the air valve. This needle valve stem 24, is provided with a head 25, which slides loosely in the socket 10, of the bushing 11, and the valve is kept on its seat by the light coiled spring 26, interposed between the 75 head 25, and the base of the socket.

27 is a screw threaded adjusting rod, with milled head 28, which rod extends down in to the socket 10 around the coiled spring 26, and by advancing or retracting this rod 80 the lift of the check valves is adjusted as desired. 35 is the packing and 36 the gland forming a stuffing box for this adjusting rod. The length of the needle valve 23, with its stem is such that when the air valve 6 and 85 needle valve 23, are both seated, a space 29 is left between the head 25, and the upper end of the stem 9, so that as the air valve is opened by the engine suction the gasoline check valve will retain its seat momentarily 90 until the head 25, is lifted by the air valve stem.

I find that this construction enables me to furnish a much more perfect mixture of air and gasoline than is possible with the ordinary generator valve constructions in which the gasoline inlet is usually drilled into the air valve seat. In the older constructions the air valve also forms the gasoline valve and the gasoline enters with the air. Better results are obtained I have discovered when the air valve opens momentarily ahead of the gasoline port. In addition to this in such constructions the gasoline enters at the side of the air inlet, so that there is much less suction on the gasoline than there is in my construction in which the gasoline is delivered centrally of the air inlet. By the introduction of the gasoline into the center of the current of inrushing air a more per- 110

fect mixture of the two gases is obtained. Moreover with my construction there is no liability of leakage of gasoline when the engine is at rest. Heretofore any failure of 5 the air valve to seat itself tightly, either from wear of the valve or dirt on the seat, or from any other cause, has resulted in a leakage of gasoline, and the gasoline supply has had to be cut off to insure against 10 leakage. This shutting off of the gasoline supply is very disadvantageous, for when the gasoline **needle** valve has been adjusted by experiment to furnish the proper amount of gasoline required for a perfect mixture 15 under any existing conditions of atmosphere or temperature, any further manipulation of the gasoline valve destroys at once the proper adjustment, which can only be again determined by further experiment.

20 The supply of the perfect mixture from the mixing chamber 2, to the engine cylinder is fully controlled by the butterfly throttle valve 30, mounted on the stem 31, with operating handle 32. Mounted on the stem 31, 25 is the packing 33, with stuffing box cap 34. The stem 27 is also provided with packing 35, held in place by the gland 36. When the proper mixture has been determined by setting the gasoline supply valve, for varying 30 speeds the supply is fully controlled by this throttle valve. In order to hold the stem of this valve in fixed position, and to prevent the jarring of the engine from disturbing its position, I provide a set screw 37, which 35 takes through an elongated boss 38 in the casing, and bears upon a coiled spring 39, interposed between the set screw and the plunger 40. The plunger is thus held under spring pressure against the stem 31, of 40 the throttle valve, which holds the valve in any position it may be set.

In order to prevent dirt or sediment in the gasoline from passing into the mixing valve, and to assist in the condensation of

any water in the gasoline, I provide a gauze 45 screen 41 for the gasoline pipe. This screen is set in a socket in the outer end of the extension of the casing through which the gasoline is introduced and held in place by a suitable washer while 42 is the coupling 50 sleeve screw threaded in the end of the pipe 4, and 43 the coupling nut, the seat ends of the coupling sleeve and casing being formed with concave and convex surfaces to form a tight joint. In passing through the wire 55 screen 41, any moisture in the gasoline is condensed and collects in the chamber 44, whence it runs down into the receptacle 45, formed in an enlargement on the casing below the gasoline inlet, and as the water 60 accumulates it is discharged through the port 46, normally closed by the valve 47.

Having thus described my invention what I claim as new and desire to secure by Letters Patent, is:

In a device of the character specified, a carbureting chamber, a valve for controlling the supply of gasoline thereto, a check valve for the air and a check valve for the gasoline, the air valve provided with a hollow 70 stem to receive and guide the stem of the gasoline check valve, with the inlet for the gasoline centrally of and immediately below the air check valve, the gasoline check valve stem extending beyond the hollow stem of 75 the air valve and having a head in the pathway thereof but normally out of contact therewith whereby the two check valves will be opened in succession, and a coiled spring bearing between the casing and the head of 80 the gasoline valve to hold the same to its seat, with a rod for controlling the lift of the check valves and external means for advancing and retracting said rod.

FLOYD L. SWANBERG.
